(57) CLAIM

The ornamental design for a thermal ice scraper, as shown and described in FIGS. 1 through 6.

DESCRIPTION

FIG. 1 is a perspective view of a thermal ice scraper showing my new design;

FIG. 2 is a front view thereof;

FIG. 3 is a top view thereof;

FIG. 4 is a back view thereof;

FIG. 5 is a bottom view thereof; and,

FIG. 6 is a left side view thereof, a right side view being a mirror image of the left side view.
